Primary Examiner — Michael A. Pratt*Assistant Examiner* — Michelle E Wilson(74) *Attorney, Agent, or Firm* — Li & Cai Intellectual Property (USA) Office(57) **CLAIM**

The ornamental design for a “cosmetic brush cleaner,” as shown and described.

DESCRIPTION

FIG. 1 is a perspective view of a cosmetic brush cleaner showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view viewed from another visual angle thereof;

FIG. 9 is a cross-sectional view taken along a line A-A of FIG. 6; and,

FIG. 10 is a cross-sectional view showing a usage status of the cosmetic brush cleaner.
